UNITED STATES PATENT OFFICE.

FREDERICK SAMUELSON, OF RUGBY, ENGLAND, ASSIGNOR TO GENERAL ELECTRIC COMPANY, A CORPORATION OF NEW YORK.

VALVE MECHANISM.

1,106,895.

Specification of Letters Patent. Patented Aug. 11, 1914.

Application filed February 1, 1909. Serial No. 475,420.

To all whom it may concern:

Be it known that I, FREDERICK SAMUELSON, a subject of the King of Sweden, residing at Rugby, England, have invented certain new and useful Improvements in Valve Mechanism, of which the following is a specification.

This invention relates to valve mechanism for controlling the supply of steam or other motive fluid to a prime mover such for example as a turbine, and more particularly to turbines normally using steam at relatively low pressure received from any suitable source such as the exhaust of a high pressure turbine or reciprocating engine.

In cases where a low pressure turbine is operated as above described, it happens at times that the supply of low pressure motive fluid is insufficient for the work required of the turbine and yet it may not be advantageous or desirable to provide a separate high pressure stage and valve gear to supply additional energy to the low pressure turbine at such times.

The object of my invention is to provide a valve mechanism by which the low pressure turbine may be normally supplied with motive fluid at low pressure and by which when said source of supply fails or becomes insufficient, motive fluid will be admitted from a source at higher pressure, said fluid being expanded or throttled down to a suitable pressure before entering the turbine.

The valve mechanism in the embodiment of the invention illustrated and described herein comprises a low pressure equilibrium valve for normally admitting low pressure steam to the turbine and a high pressure balanced piston valve mounted on the same spindle as the equilibrium valve for admitting steam from a boiler or other source at higher pressure to the casing of the low pressure valve to supplement the low pressure supply when conditions require it, the high pressure steam being brought to a lower pressure before entering the turbine. Both valves are operated by a hydraulic relay cylinder controlled by a governor or speed responsive device, and the valves are

so arranged on their spindle that the high pressure valve does not open until the low pressure valve is opened sufficiently far to pass steam up to the full capacity of the supply pipe. Under these conditions, so long as there is a supply of low pressure steam equal to the demand on the turbine, the speed is kept up and no high pressure steam is supplied, but if the supply is not sufficient, the speed falls and the valve opening more, the requisite quantity of steam from the high pressure source is supplied to the turbine. The high pressure valve is also of use for starting up when with a self-contained plant no power is available for the air and circulating pump motors until the turbine is running. In this case, the low pressure supply pipe is shut off and as when the turbine is standing idle the high pressure valve is wide open, on turning on the high pressure steam the turbine starts up non-condensing. When up to speed and a vacuum has been obtained, the low pressure supply can be opened up so that the turbine will operate in its normal manner.

In the accompanying drawing illustrating one of the embodiments of my invention, Figure 1 is a diagrammatic view of a power system including a reciprocating engine and low pressure turbine provided with my invention; and Fig. 2 is a sectional view of the valve mechanism supplying steam to the turbine.

The non-condensing reciprocating engine 3 receives live steam from any suitable source through the conduit 4. The exhaust from its cylinder passes into the conduit 5 provided with a stop valve 6. In this conduit between the stop valve and the low pressure turbine 7 is located the valve mechanism 8 for regulating the supply of motive fluid to said turbine. An accumulator for storing exhaust steam in excess of the demand of the turbine may be connected to or form a part of the conduit 5 and deliver its stored energy to the turbine to supplement the supply from the engine under certain conditions. The turbine 7 may be of any well known construction. It is provided with a free or atmospheric exhaust 100

valve α and a condenser 9 and the usual auxiliary apparatus, and may drive any suitable load such as an electric generator. The motors for the auxiliary apparatus may be 5 driven by the current from the generator, if desired.

In Fig. 2 both the high and low pressure supply valves are illustrated at the top of their movement with the steam entirely shut off. 10 indicates a valve casing for the low pressure supply valve having an inlet 11 receiving low pressure steam from the conduit 5 and an outlet 12 through which steam passes to the turbine. Mounted on or forming 15 a part of the casing 10 is another casing 13 for the high pressure supply valve provided with an inlet 14 for the high pressure steam supply from a conduit 15 leading from any suitable source which may be 20 the same source as that for the engine 3 if desired. The low pressure valve 16 and the high pressure valve 17 are secured in fixed relation on the lower portion of a common stem 18. The heads of the balanced 25 low pressure valve 16 are indicated at 19, while the high pressure valve 17 consists of two piston heads 20 connected by a hollow stem 21 surrounding the main valve spindle 18 and having a bore of larger diameter 30 than the spindle. Ducts or passages 22 connect the clearance between the spindle 18 and the bore of the stem 21 with the space 23 below the lower head 20 and with the space 24 above the upper head 20, and serve 35 to equalize the pressure on its opposite ends and thus balance the valve 17. The casing 13 is provided with a sleeve 25 within which the valve 17 is located. This sleeve has two sets of ports 26, 27, the flow through which 40 is controlled by said valve. The valve stem 18 has a suitable stuffing box 28 that prevents leakage to the atmosphere. Supported on the casing 13 is a hydraulic cylinder 29 provided with a piston 30 secured to the 45 valve stem 18. The admission of liquid under pressure to this cylinder to move the piston and the valves connected therewith is regulated in any well known manner by suitable mechanism under the control of a 50 speed responsive device driven directly or indirectly from the turbine shaft.

55 32 indicates a speed governor driven by the turbine. The sliding collar 33 of the governor actuates the lever 34, one end of which is pivotally attached to the piston rod 18 to form a follow-up device. To the lever is attached a rod 35 for actuating the pilot valve 36, the latter serving to control the admission of fluid to and its escape from 60 the cylinder 29 of the motor. Fluid under pressure is admitted to the pilot valve chest by the conduit 37 and escapes by the conduit 38.

Under ordinary conditions the valve 16 65 will be moved downward from its position,

Fig. 2, and opened to a greater or less extent under the control of the governing mechanism of the turbine to permit steam to flow from the conduit 5 through the valve casing 10 to the turbine. Steam at 70 high pressure from the conduit 15 passes through the inlet port 14 to the annular space 31 surrounding the sleeve 25 and thence through the ports 26 to the space between the heads 20. When the supply of 75 low pressure steam is insufficient to maintain the desired speed of the turbine the valves will be moved still farther downward so that the lower piston 20 uncovers the ports 27 and permits steam from the 80 high pressure source to pass into the main valve casing whence it flows through the valve 16 to the turbine with the low pressure supply. In passing through the ports 27 the steam is expanded and throttled 85 down to a pressure corresponding to the load on the turbine.

In accordance with the provisions of the patent statutes, I have described the principle of operation of my invention, together 90 with the apparatus which I now consider to represent the best embodiment thereof; but I desire to have it understood that the apparatus shown is only illustrative, and that the invention can be carried out by other 95 means.

What I claim as new and desire to secure by Letters Patent of the United States, is,—

1. In combination, a prime mover which receives motive fluid from a plurality of 100 sources at different pressures, a governor controlled valve which regulates the admission of fluid from a source at relatively low pressure to said prime mover, and means also controlled by the governor for admitting fluid from a source at higher pressure through said valve to the prime mover when the supply of low pressure steam is insufficient to drive the load.

2. In combination, a prime mover which receives motive fluid from two sources at different pressures, a governor controlled valve which regulates the admission of fluid from a source at relatively low pressure to the prime mover, and a second valve 110 also controlled by the governor which admits fluid from a source at higher pressure through the first valve to the prime mover when the supply of low pressure fluid is insufficient to drive the load, said second valve 115 reducing the pressure of the high pressure fluid before it enters the turbine.

3. In combination, a prime mover which receives motive fluid from two sources at different pressures, a valve regulating the supply of fluid from a source at relatively 120 low pressure to the prime mover, and a second valve in longitudinal alinement with the first valve which admits fluid from a source at higher pressure when the supply 125

of low pressure fluid is insufficient to drive the load, the motive fluid from the second valve passing through the first and being delivered to the prime mover by the same 5 conduit as the low-pressure fluid.

4. In combination, a prime mover which receives motive fluid from two sources at different pressures, a valve which regulates the admission of fluid from a source at relatively 10 low pressure to the prime mover, a stem for the valve, a second valve actuated by said stem which admits fluid from a source at higher pressure to the prime mover when the supply of fluid at low pressure is 15 insufficient to drive the load, and a conduit which receives the motive fluid from both valves and delivers it to the same part of the prime mover.

5. In combination, a prime mover which receives motive fluid from two sources at different pressures, a governor controlled valve which regulates the admission of fluid from a source at relatively low pressure to the prime mover, a stem for the valve, a second 20 valve mounted on said stem which admits fluid from a source at higher pressure to the prime mover when the supply of low pressure fluid is insufficient to drive the load, the motive fluid from the second valve passing 25 through the first, and a conduit that is common to and receives the fluid from both sources after it passes through the valves.

6. In combination, a prime mover which receives motive fluid from two sources at different pressures, a governor controlled valve which regulates the admission of fluid from a source at relatively low pressure to the prime mover, a stem for the valve, and a second 30 valve mounted on said stem and controlled by the governor which admits fluid from a source at higher pressure when the supply of low pressure fluid is insufficient to drive the load, said second valve reducing the pressure of the high pressure fluid before 35 it enters the prime mover.

7. In combination, a prime mover which receives motive fluid from two sources at different pressures, a valve for regulating the flow of fluid from a source at relatively low pressure to the prime mover, a stem for the valve, a second valve on the stem which regulates the flow of fluid from a source at higher pressure to the prime mover, and a governor-controlled motor for actuating the 40 valves, said valves being so arranged and constructed that the low pressure valve is opened by the motor to permit full flow therethrough before the high pressure valve is opened.

8. In combination, a prime mover which receives motive fluid from two sources at different pressures, a valve casing, a valve therein for regulating the flow of fluid from a source at relatively low pressure to the

prime mover, a stem for the valve, a sleeve 65 mounted in the casing and provided with ports, a second valve on the stem which regulates the flow through said ports from a source of fluid at higher pressure, the pressure of said fluid being reduced as it flows 70 through said ports to the prime mover, and a governor-controlled motor for actuating the valves which opens the second valve after the first has been opened to permit a full flow therethrough, said motor comprising a cylinder 75 mounted on the casing, and a piston in the cylinder which is secured to the stem.

9. In combination, a high pressure engine, a low pressure engine receiving motive fluid from the exhaust of the high pressure engine, a governor-controlled valve which regulates the admission of the exhaust fluid to the inlet end of the low pressure engine, a second valve controlled by the governor which admits fluid from a source at higher 80 pressure to said inlet end when the supply of exhaust fluid is insufficient to drive the load on the low pressure engine, communicating casings for the valves through which fluid flows from one to the other, and a motor that 85 is common to and actuates both valves.

10. In combination, a high pressure engine, a low pressure turbine receiving motive fluid from the exhaust of the engine, a balanced valve controlling the admission of 90 exhaust fluid from the engine to the turbine, a stem for the valve, and a second balanced valve mounted on said stem for admitting fluid from a source at higher pressure to the turbine under certain conditions, said second 95 valve expanding the fluid admitted through the second valve down to a suitable pressure before it enters the turbine.

11. In combination, a high pressure engine, a low pressure turbine, a conduit supplying exhaust steam from the engine to the turbine, a valve casing in the conduit adjacent the turbine through which steam flows to said turbine, a balanced valve in the casing which regulates the flow of exhaust 100 steam to the turbine, a stem for the valve, and a second balanced valve on said stem which regulates the flow of steam from a source of higher pressure to said casing, said second valve reducing the pressure of the 105 high pressure steam before it enters said casing.

12. In combination, a high pressure reciprocating engine, a low pressure turbine, a conduit supplying exhaust steam from the 110 engine to the turbine, a stop valve in the conduit, a governor controlled valve mechanism in the conduit between the stop valve and the turbine which regulates the flow of exhaust steam to the turbine and supplies steam 115 from a source of steam at higher pressure when the supply of exhaust steam is insufficient to drive the load.

on the turbine, a conduit supplying high pressure steam to said valve mechanism, a stop valve in said conduit, a condenser, a conduit between the turbine and the condenser, a free-exhaust conduit leading from the turbine to the atmosphere, and a valve controlling said free-exhaust conduit.

In witness whereof, I have hereunto set my hand this twentieth day of January, 1909.

FREDERICK SAMUELSON.
